FINGER LOCK FOR TROUSER CREAMER

Edgar D. Lee, Jr., St. Louis, Mo., assignor to Lee-Rowan Company, St. Louis, Mo., a corporation of Missouri

Application May 4, 1956, Serial No. 582,785

1 Claim. (Cl. 287—58)

This invention relates to improvements in finger locks for garment stretchers and trouser creasers, and in particular is concerned with a lock which has means for receiving fingers upon it so it may be readily moved to and from the locking position.

In the past, trouser creasers and garment stretchers have been made in the form of expandable, more or less rectangular metal strips, which are adjustable so that they may be made, in slightly tapering form, to fit within trousers or other garments, as shown in the Hansen Patent No. 2,204,354. Such devices, which hereinafter shall be termed garment creasers, have been made in the form of two strips facing one another which are curved at their ends in a generally U-shaped fashion and are telescopically slidable on one another by sleeves. These strips can be locked at any position by manipulation of a lock. The conventional lock in the past has been a loose fitting rectangular sleeve which was movable upon a raised locking portion in one of the strips and which would bind thereagainst to lock one strip against the other by friction. Such locks have been quite objectionable as in a good many instances they would be jammed and would resist unlocking. Friction is more or less evenly distributed due to the gentle taper of the raised portion so as to bind against the interior of the sleeve and resist unlocking. This has been particularly objectionable when creasers have been used by housewives who have at times found this feature to be a source of some trouble, as at times a great deal of force was required to unlock the sleeve.

By means of this invention, there has been provided an improved finger lock which has finger grasping portions upon it so that it may be readily moved into and out of the locking position. The finger lock is provided with opposed recesses on opposite sides of the strips upon which it is used and is adapted to receive the thumb and the forefinger of the operator for the most efficient utilization of these members. A great deal of force can be exerted upon the finger lock of this invention through the design of the finger receiving portions without any portion of the lock cutting into the fingers as has been the case in the past with the conventional rectangular sleeve lock. Further, this improved finger lock herein disclosed may be made from stamped metal and requires no complicated machine or forming operation. It is rugged and inexpensive in cost and can be readily operated into and out of the locking position under substantially all conditions.

Accordingly, it is a primary object of this invention to provide a finger lock for garment creasers which has means upon it for receiving the fingers of an operator's hands so that it may be easily manipulated into and out of locking position.

A further object of this invention is to provide a finger lock for a garment creaser which is made out of a single piece of metal and is so formed as to receive an operator's fingers in recesses therein in a comfortable fashion to allow application of force without cutting into the fingers.

2

Still another object of this invention is to provide an improved finger lock for garment creasers made out of a single piece of flat metal which is formed so as to have a pair of spaced raised portions on either side of the expandable pieces of metal which are adapted to be locked together with the raised portions being adapted to receive an operator's fingers therebetween for proper grasping of the lock.

Still another object of the invention is to provide an improved finger lock for garment creasers made of a single piece of flat metal in a generally figure 8 configuration with openings at the opposed ends of the loops to receive expandable pieces of metal strips therein and with the operator's fingers being adapted to be received comfortably between and on opposite sides of the loops.

Still another object of this invention is to provide an improved finger lock for garment creasers made of a simple metal stamping which can comfortably receive an operator's fingers forcibly applied thereto and which is rugged in construction and inexpensive in cost.

Further objects of this invention will appear in the detailed description which follows and will be further apparent to those skilled in the art.

For the purpose of illustration of this invention, reference is made to the accompanying drawings showing a preferred embodiment of this invention. It is to be understood that the drawings are for the purpose of example only and that the invention is not limited thereto. In the drawings:

30 Figure 1 is a plan view showing a portion of a garment creaser device equipped with the finger lock of this invention;

35 Figure 2 is an enlarged view in front elevation showing the finger lock upon the expandable strips in locking position;

Figure 3 is a view in section taken on the line 3—3 of Figure 2 showing the left end of the finger lock;

Figure 4 is a view in section taken on the line 4—4 of Figure 2 showing the finger locking elements at the right end of the finger lock; and

33 Figure 5 is a view in vertical section taken along the axis of the finger lock.

In Figure 1, a portion of a garment creaser, generally indicated at 10, is shown in fragmentary form. It is to be understood that the bottom portion of the device is similar to the top and that a finger lock to be described can be similarly employed thereupon. The garment creaser 10 includes a metal strip 11 and a metal strip 12 which are movable toward and away from one another and adapted to be locked in a set position by a finger lock 13.

The strip 11 includes a leg portion 14 while the strip 12 also includes a leg portion 15 as shown more particularly in Figure 2. The end of the leg 14 has secured to it a rectangular sleeve 16 which fits loosely over the leg 15. In similar fashion, the leg 15 has secured to it a rectangular sleeve 17 which fits loosely over the leg 14. Through the sleeves, the legs are movable toward and away from one another and are kept in rigid parallelism. Thus, the legs may be telescoped upon one another to bring the metal strips 11 and 12 toward one another or expansion may be effected in a reverse fashion. In similar manner, the bottom of the garment creaser (not shown) may be adjusted.

65 In order to provide for the locking of the two strips together, the leg 15 is provided with an offset and tapering portion generally indicated at 21. This may be formed by a conventional bending operation by putting a sharp bend 22 in the leg 15. The gently tapering portion 23 when formed may actually be straight but since it is secured to the sleeve 17, it may assume a generally tapering configuration.

The lock 13, as shown more particularly in Figures 2, 3, 4 and 5 is formed of a single piece of flat sheet metal which is bent to shape. It is provided with two finger receiving portions 25 and 26 on opposed sides and these finger receiving portions are between the loops of the generally numeral 8-shaped configuration. The right end, or locking loop, is indicated at 27 and the left end, or guide loop is indicated at 28. The locking end of the loop 27 is provided with a rectangular-shaped opening 31 within which are received the strip locking portion 23 of leg 15 as well as leg 14. The loop 28 is similarly provided with a rectangular opening 32 which guideably receives the end of the leg 15 and leg 14, but as shown in Figure 3, there is no locking relationship provided when the finger lock is in the lock position.

The locking member 13 is very simply constructed and is quite rugged. It is formed of sheet metal, as mentioned above, and the only machining operation required is the cutting or stamping out of the holes 31 and 32. When formed in the configuration shown in Figure 2, the bases of the finger receiving recesses 25 and 26 are spaced closely adjacent to one another and are of sufficient width to receive the fingers and also to fit close to the legs 14 and 15. Further, because the locking opening 31 in the loop 27 is formed from a vertically disposed member, there is no tendency to spring apart the lock and the lock cannot be distorted and is of a very permanent nature.

Operation

The legs 14 and 15 of the garment creaser are shown in locked relationship in Figures 2 and 5. This relationship is achieved by moving the lock 13 to the right as far as it will go. As it is moved to the right, it causes the locking portion 23 of leg 15 to bind in the opening 31 of the loop 27 because of the confining relationship of the opposite edge of the opening which is forced against the leg 14 at the other side thereof. As this binding or locking relationship is achieved, the leg 15 will be pressed tightly against leg 14 so that relative movement therebetween is not possible.

This locking relationship is shown in Figure 4 and in Figure 5 where it is seen that the exterior surfaces of the locking portion 23 of leg 15, and the leg 14 bear against the edges of the opening 31, in a tight fit. On the other hand, it will be noted that the loop 28 has its opening 32 loosely disposed over the exterior surfaces of the end of the leg 15 and leg 14 so that the tight locked fit is accomplished only through one loop and opening at the right end of the lock. This provides for obtaining a sure and efficient lock while, at the same time, preventing too much friction or locking force to be applied so that removal is difficult.

The lock 13 is very easily removed from the locking

position shown in Figures 2 and 5 by placing the thumb and forefinger in the finger receiving portions 25 and 26 and reversing the locking force to move the lock in the left hand direction as viewed in Figures 2 and 5. The finger receiving portions 25 and 26 are so designed that the fingers may be applied against the opposite interior sides of the loop 28 with a large disposition of finger force without discomfort to the fingers. Thus, the lock may be easily removed from the position shown in Figures 2 and 5, and the device is easily converted to the unlocked condition. Reverse movement of the lock again to the right hand direction where the fingers bear against the opposite interior sides of the loop 27 will then effect the locking operation, with a return to the condition shown in Figures 2 and 5.

Various changes and modifications may be made in this invention and will be apparent to those skilled in the art. Such changes and modifications are within the teaching of this invention as defined by the scope of the claim appended hereto.

What is claimed is:

A lock for two relatively movable rigid strips, one of which is provided with an inclined offset portion, said lock being adapted to enclose a portion of said strips and bind against the inclined portion, said lock comprising a body formed from rigid strip material having opposed ends disposed at right angles to said movable strips and provided with rectangular shaped openings to receive the strips therethrough whereby the lock may be moved toward and away from the offset portion, corresponding to locking and unlocking positions, respectively, said body being further provided with gently curved recessed means in opposed surfaces of said lock intermediate the ends adapted to bear against the outside faces of said strips and to receive the fingers of an operator for firmly grasping the lock, said body having the general configuration of the figure 8 with the opposed ends of the loop being in the form of vertical portions disposed as aforementioned at right angles to the movable strips and with the finger receiving recess means being spaced from one another and oppositely disposed between the loops of the figure 8.
